SELF-CLAMPING SHELF EDGING

Edwin L. Beckwith, Newton, Mass.

Application June 17, 1959, Serial No. 56,395

Term of patent 14 years

(Cl. D59—2)

FIG. 1

FIG. 2

Fig. 1 is a view in elevation of a self-clamping shelf edging, showing my new design; and

Fig. 2 is a sectional view taken on the line 2—2 of Fig. 1 showing the continuous top and bottom flanges.

I claim:

The ornamental design for a self-clamping shelf edging, as shown.
